(57) **CLAIM**

The ornamental design for a hatch for vehicles, as shown and described.

DESCRIPTION

2. Hatch for vehicles

2.1 : Perspective

2.2 : Front

2.3 : Back

2.4 : Left

2.5 : Right

2.6 : Top

2.7 : Bottom

2.8 : Perspective view in use

The broken lines illustrate portions of the hatch for vehicles which form no part of the claimed design. The broken lines depicting a vehicle in FIG. 2.8 show environmental structure that forms no part of the claimed design.
